US00D494654S1

(12) **United States Design Patent** (10) Patent No.: **US D494,654 S**
Macaulay et al. (45) Date of Patent: **** Aug. 17, 2004**

(54) **FLUIDIC CARTRIDGE FITTINGS**

(75) Inventors: **Frank Delmar Macaulay**, Cincinnati, OH (US); **Judd Dylan Olson**, Minnetonka, MN (US); **David James Emmons**, Plymouth, MN (US); **John Paul Boros**, Maple Lake, MN (US)

(73) Assignee: **Procter & Gamble Co.**, Cincinnati, OH (US)

(**) Term: **14 Years**

(21) Appl. No.: **29/180,628**

(22) Filed: **Apr. 25, 2003**

(51) LOC (7) Cl. **23-01**

(52) U.S. Cl. **D23/209**

(58) Field of Search **D23/207, 209; 210/232, 443, 444**

Primary Examiner—Robin V. Taylor

(74) Attorney, Agent, or Firm—S. Robert Chvey; Richard Alexander

(57) **CLAIM**

The ornamental design for fluidic cartridge fittings, as shown and described.

DESCRIPTION

FIG. 1 is a rear elevational view of fittings of a fluidic cartridge showing our new design;

FIG. 2 is a top plan view thereof;

FIG. 4 is a left side view thereof;

FIG. 4 is a front elevational view thereof;

FIG. 5 is a bottom plan view thereof;

FIG. 6 is a right side view thereof; and,

FIG. 7 is a perspective view thereof.

The parts shown in broken lines in FIGS. 1–7 are shown for illustrative purposes only and form no part of the claimed design.

1 Claim, 3 Drawing Sheets
